ETAGERE

George V. Goulder, Shaker Heights, Ohio, assignor to International Products and Services, Inc., Cleveland,
Ohio

Filed Apr. 9, 1973, Ser. No. 348,986

Term of patent 14 years

Int. Cl. D6—04
U.S. Cl. D6—186

FIG. 1 is a perspective view of an etagere showing my new design;

FIG. 2 is a front elevational view;

FIG. 3 is a side elevational view;

FIG. 4 is a top plan view; and

FIG. 5 is a bottom plan view.

I claim:

The ornamental design for an etagere, as shown.
